UNITED STATES PATENT OFFICE.

HERBERT P. HOLLNAGEL, OF SWAMPSCOTT, MASSACHUSETTS, ASSIGNOR TO GENERAL ELECTRIC COMPANY, A CORPORATION OF NEW YORK.

COMBINED RESISTOR AND FUSE.

Application filed January 6, 1926. Serial No. 79,683.

The present invention relates to protective devices for electrical apparatus and especially for protecting against the destructive action of high potential, high frequency currents or surges of electricity having a steep wave front.

The object of my invention is the provision of a compact protective device which shall function effectively to open the circuit protected thereby quietly and without causing other surges or transients in the system, and which shall absorb such energy as may be characterized by transient or surge phenomena originating anywhere in the circuit to thereby protect such apparatus or portions of the circuit conductor as are liable to injury from such phenomena.

One of the instances where serious troubles have been experienced from electrical transients is in condenser installations which, as is well known, are usually made up of a plurality of units, of substantial capacity, joined in parallel. In practice condensers probably fail because of transients originating from causes remote to the condenser. In the failure of a condenser, it is probable that transients are set up by the sudden breakdown of some one unit and the ensuing opening of the circuit thereto by the functioning of a fuse or other protective device intercalated therein. These transients probably cause incipient failure in the other condenser units joined in parallel therewith, ultimately resulting in their breakdown.

It is well known that the resistance of conductors increases enormously with rise in frequency, probably several hundred per cent in a frequency rise of from 60 cycles to fifty thousand cycles, depending upon the diameter of the conductors, their permeability and resistivity. I make use of the constant current characteristic of the conductors, and these characteristics in their relation to transients, by connecting in series with a fuse, a non-inductive resistance conductor of relatively short length (these may consist of any of the standard resistance wires or materials having high permeability), which under normal operation consumes an insignificant amount of energy and yet upon switching, blowing of a fuse, or other abnormal operation of the circuit, such as short circuiting or arcing, serves effectively to ab-

sorb the energy produced by the sudden rise in voltage or a possible ensuing rise in frequency, or both.

Certain embodiments of the invention are shown in the accompanying drawing, in which Fig. 1 is a side elevation of a cartridge fuse with a non-inductive resistor element combined therewith; Fig. 2 is a vertical section thereof; Fig. 3 is a circuit diagram; Fig. 4 is an elevation of a modification in which the cartridge fuse is mounted alongside a non-inductive resistor element provided with dissipating vanes; Fig. 5 is an elevation of a further modification in which non-inductive resistor elements with dissipating vanes are mounted upon both ends of the cartridge fuse, and Fig. 6 is a circuit diagram of the latter arrangement.

The resistor member, as shown, consists of a base 1 of insulation having a coil of insulated resistance wire 2 reversely or non-inductively wound about the larger end of the base and protected by an incasement of tape or other fibrous material wrapped thereabout. The coil lead wires 4 and 5 are threaded through passageways 6 and 7 in the small end of the base.

The fuse member is similar to the ordinary cartridge fuse and comprises a tubular barrel 8 of insulation with a thimble-shaped terminal 9 at its lower end and a ferrule-shaped terminal 10 at its upper end. The upper end of the barrel receives the smaller end of the base which is secured therein by set screws 11.

The fusible element 12 is the ordinary metal strip surrounded by a tubular envelope 13 of sheet asbestos. The lower end of the fusible element 12 is attached to the terminal 9 and the upper end to a metal bush 14 secured to the lower end of the base.

The coil lead wire 4 is secured to the terminal 10 and the other lead wire 5 is attached to the bush 14, and the complete device is connected in circuit by insertion in the usual fuse block with the contact terminal 10 next the power line and the terminal 9 next the condenser unit to be protected, as indicated in Fig. 3.

Upon the interruption of the current to the condenser unit by blowing of the fuse under short circuit, a surge of current takes place which dissipates its energy in the non-inductive resistance coil 2 without causing dis-

turbance of other devices connected to the circuit.

To care for the situation where continued arcing or interrupted short circuit conditions persist in the line, as a consequence of which continued or interrupted transients of a relatively high frequency persist over a period of time, and resulting in the absorption of energy by the resistor, I provide the latter with dissipative means.

As shown in Fig. 4, the energy dissipative means consists of a helical vane or Archimedean spiral 15 of metal coiled about a core bar 16 having metal thimbles 17 at its ends adapted to enter contact clips 18, the lower of which is provided with a binding screw 19 for connection with the line wire. The insulated resistance wire 2' is connected at one end by a binding screw 20 to the lower thimble 17 and passed through the trough of the spiral 15 to the upper end thereof where it turns about a peg 21 carried by bar 16 and repasses through the spiral trough to the lower end thereof and joined by a binding screw 22 to the lower contact clip 23 of the enclosed fuse 8'. The resistor clips 18 and the fuse clips 23 are mounted on an insulating base so as to support the resistor and the fuse beside each other and permit renewal of the latter without disturbance of the former. With the resistance wire 2' protected by insulation, the core bar 16 may be of either insulating or conducting material, but in case the latter material is used it is provided with a slot parallel to its axis in order that it may function as an open-circuited secondary in the presence of the variable currents carried by the resistance wire. In some cases it also is advantageous to provide the radiating vanes with cross slots at intervals for a like purpose.

As shown in Fig. 5, the end terminals of the cartridge fuse 8'' are provided with hollow insulating core bars 16'', on each of which is mounted a spaced series of metal disks or washers 24 and the insulated resistance wire 2'' is connected by a binding screw 25 to the respective fuse terminals and passed through the innermost washer 24 and coiled right-handedly in the first space between washers, then passed through the second washer and coiled left-handedly in the second space, and so on through the series in alternate directions until it finally passes through the end-most washer and is threaded through the hol-

low bar 16'' to connect with the fusible element as in the first modification.

Fig. 6 shows a diagram of connections embodied in the fuse construction of Fig. 5 and from which it will be apparent that the non-inductive resistance disposed at both ends of the fusible link serves to limit the transient effect thereon in both directions. Transients arising from the continuance of an arc as a result of fusion of the fuse link are dissipated not only before the entering line but also before entering the apparatus, thus protecting against surge or transient phenomena during both alternations of each cycle of such frequencies.

While I have shown and described the best embodiments of the invention known to me, I do not desire to be restricted thereto.

What I claim as new and desire to secure by Letters Patent of the United States, is,—

1. The combination of an electric fuse, spaced metallic vanes, and a reversely wound resistance coil connected in series with said fuse and having its convolutions distributed in the spaces between said vanes.

2. The combination of a fuse member comprising a fusible element enclosed in an insulating cartridge having external contacts, and a non-inductive resistance member comprising an insulating base mounted on said cartridge and supporting a coil of resistance conductor wound non-inductively and connected in series to said fusible element and said fusible element and said resistance conductor having terminal connection with said external contacts, and radiating vanes so disposed as to radiate the energy developed by said resistance conductor.

3. The combination of a fusible element, an insulating cartridge about said element, a non-inductive resistance member mounted on said cartridge and connected in series with said element, and means also mounted on said cartridge to radiate energy from said resistance member.

4. The combination of a fusible element, an insulating cartridge about said element, a non-inductive resistance member mounted on said cartridge and connected in series with said element, and metallic vanes also mounted on said cartridge to radiate energy from said resistance member.

In witness whereof, I have hereunto set my hand this fourth day of January, 1926.

HERBERT P. HOLLNAGEL.
